6 Claims. (Cl. 36—8.5)

In the known process for the manufacture of footwear, the upper leather is connected to a continuous insole by sewing, nailing or other means of attachment, a filler being inserted in the front part of the shoe or boot and a relatively flexible stiffening consisting of a thin plate of wood, cardboard or metal in the instep and heel part, and the continuous outer sole is attached under the insole. The stiffening inserted between the insole and the outer sole is partly formed as a support for the foot, but it still leaves an empty space between the foot and the inner sole, so that the bones of the foot, and particularly the heel bone, are not sufficiently supported and can sink. Further adaptation of the shoe involves difficulties because the outer shape of the shoe cannot be changed. The edge of the insole serving for the attachment of the upper must have the same level on both sides, whereas the inner surface of the shoe rises to a different level on both sides in accordance with the shape of the foot.

The subject of the present invention is footwear in which the rear part of the shoe is provided with a non-flexible stiffener of material which resists bending forces, the lower margin of which is preferably provided with a welt for the attachment of the upper, and the lower side of which is flat to conform with the shape of the sole, whilst the upper part is adapted exactly to the shape of the foot, filling material being used if necessary.

The non-flexible stiffener can replace the other parts of the sole and in the vicinity of the ball of the foot it can be connected with the front parts of the sole which abut obliquely against its front edge, whereas the upper and if necessary the heel-covering are attached in a groove at the level of the edge of the insole. The rear portion of the insole can serve as covering sole or may also be split and cover the non-flexible stiffener above and below, the upper being connected with the bottom part of the rear insole by a seam. The stiffener may further consist of two mutually supporting metal plates of which the upper corresponds to the shape of the foot and the lower to the shape of the sole.

At its heel end and at the sides the non-flexible rear part of the stiffener is carried up so far that the inner sole gradually merges into the shape of the shoe, and the rear cap is held by the back surface of the heel part. By strong curving of the bottom of the shoe the heel bone and the adjoining bones of the instep are securely supported, and in cases of sunken instep a resilient pressure may be exercised thereon if necessary,

by which malformations of the foot can be corrected.

Several embodiments of the invention are shown by way of example in the accompanying drawings, in which:—

Fig. 1 is a longitudinal section through the middle of a shoe having a non-flexible stiffener and an insole split in the rear portion.

Fig. 2 is a cross section along the line II—II of Fig. 1.

Fig. 3 is a longitudinal section of a shoe, the upper of which is attached directly in a cut-away portion in the bottom of the shoe.

Fig. 4 is a cross section through the shoe according to Fig. 3 along the line IV—IV.

Fig. 5 is a longitudinal section through the footwear according to Fig. 6 along the line V—V.

Fig. 6 is a cross section along the line VI—VI of Fig. 5.

Fig. 7 is a cross section along the line VII—VII of Fig. 5.

In the form of construction shown in Figs. 1 and 2, the insole 2 which, in the front part of the shoe, fixes the upper, is slit at the rear part of the shoe, and embraces between its upper broader half 2' and its lower narrow part 2'' which corresponds to the breadth of the sole, a stiffener 1 which consists of rigid material, particularly wood, and forms at its lower edge the usual sole edge for attaching the upper. The upper side of the stiffener 1 is formed so as to correspond exactly to the shape of the foot, whereas its lower side is formed flat so as to adapt itself to the shape of the sole. The upper part 2' of the insole completely covers the top of the stiffener 1 and gradually merges into the shape of the shoe, while the lower part 2'' of the insole is connected with the upper 6 by a connecting seam after the manner of welted shoes.

The stiffener can be firmly connected with the rear parts of the insole by means of glue or nails. At the heel, a heel portion 7 is provided in the usual manner, the front surface of which is covered by an outer sole 3 which is connected at the back with the part 2'' of the insole and in the front with the insole 2 by sewing or gluing, the filling material 4 being inserted.

In the form of construction shown in Figs. 3 and 4, the insole 2 is carried as far as the heel, without being split. The upper 6 is attached by 50 nails in a flat cut-away portion 8 of the stiffener 1 the top of which corresponds to the shape of the foot and the lower part corresponds to the shape of the sole. The heel 7, the front surface of which is also covered by the outer sole 3 and with a heel 55

tap 5, is connected directly to the rigid stiffener.

In the footwear according to Figs. 5-7 the insole 2 runs through to the rear end of the shoe and is connected in the usual manner with the upper 6 by sewing, nailing, or gluing. Under the insole and between the ends of the upper in the longitudinal centre a narrow crimped metal plate 1'' is arranged which has the same shape as the sole and which extends forward to the vicinity of the ball of the foot thus preventing the insole from sagging. A second metal plate 1' provided above the insole and corresponding exactly to the shape of the foot extends far upwards particularly on the inner side of the centre part of the shoe, so that the entire surface of the foot rests on a covering sole attached to the metal plate 1'.

The rear end of the plate 1' is rigidly connected with the lower plate 1'' by means not shown, such as a rivet, and engages at its front end by means of a downwardly directed projection 40 through a slot 41 in the insole, with the recess 42 in the lower metal plate in such manner that it can be displaced longitudinally therein. The upper metal plate exerts a pressure on the heel bone in order to correct deformations of the foot, but in case of a particularly strong counter-pressure it can move resiliently downwards, so that points of pressure cannot be produced on the sole of the foot.

The usual lasts can be used for making the footwear according to Figs. 5-7, as the upper stiffener 1' together with the covering sole 2' need be inserted in the shoe only after attaching the upper 6 with the insole resting on the last and connected with the lower metal plate 1'' and after the withdrawal of the last.

By means of the rigid stiffener according to the invention the inside of the shoe is adapted exactly to the shape of the foot, but the shoe retains the usual form as the lateral surfaces of the stiffener hold the upper in the correct position and produce at their lower edge a sole edge which has a sharp contour at the heel. The rear stiffener, which is preferably made of a single piece of material, can have any desired form on its inner surface such as that of the known orthopedical arch supports, but in contrast with these it has the advantage that it is impossible for the supporting member to slip, so that the desired correction of the foot by pressure on the foot joint can be obtained with safety.

I claim:

1. Footwear comprising at the rear part of the shoe a broad insole, a rigid stiffener arranged under said insole and conforming at its lower surface with the shape of the shoe and at its upper side with the shape of the foot, the upper side of said stiffener and the insole gradually merging into the shape of the shoe and the lower surface of the stiffener having a flat cut-away portion for attaching the upper leather.

2. Footwear comprising a rigid stiffener permanently fixed to the upper leather and the

outer sole and insole conforming at its lower surface with the shape of the sole and at its upper side with the shape of the foot and having the full width and extent of the foot at the rear thereof, that stiffener being arched to such an extent that it exercises a pressure on the anterior and the longitudinal arch of the foot in order to correct malformations of the foot.

3. Footwear comprising a rigid stiffener embraced between an upper broad flap and a lower narrow flap of the slit rear part of an insole, an outer sole and an upper, said stiffener, which has the full width and extent of the foot at the rear thereof, at its lower face being parallel to the outer sole and representing a sole edge adapted to support the upper, and at its upper face conforming throughout with the shape of the foot and gradually merging into the upper at all borders including the heel end and into the front part of the insole at a point adjacent to the ball portion.

4. Footwear comprising at the rear part of the shoe an outer sole and an insole, a rigid stiffener, which is permanently connected with said soles and has the full width and extent of the foot at the rear part thereof conforming at its upper surface with the shape of the foot, an upper leather having its marginal portion embraced between the outer sole and the stiffener, said stiffener gradually merging into the upper at all borders including the heel end and into the front part of the insole at a point adjacent to the ball portion.

5. Footwear comprising at the rear part of the shoe a broad insole, an outer sole and an upper, a stiffener permanently fixed under said insole conforming at its lower surface with the shape of the shoe and at its upper side with the shape of the foot, the upper side of said stiffener being arched to such an extent that it exercises a pressure on the lower face of the foot to correct malformations thereof, that upper side of the stiffener and the insole gradually merging into the shape of the shoe, the lower surface of said stiffener having a flat cut-away portion for attaching the upper leather.

6. Footwear comprising an outer sole, an insole and an upper, a rigid stiffener embraced between an upper broad flap and a lower narrow flap of the slit rear part of the insole, said stiffener, which has the full width and extent of the foot at the rear part thereof, at its lower face being parallel to the outer sole and representing a sole edge which supports the upper, and at its upper face conforming with the shape of the foot, but being arched to such an extent that it exercises a pressure on the lower face of the foot to correct malformations thereof, that upper side of the stiffener gradually merging into the upper at all borders including the heel end and into the front part of the insole at a point adjacent to the ball portion, said insole being connected with the upper in the front part of the shoe.

WILHELM DEUKER.
